RESONANT WAVEGUIDE BACKWARD-WAVE OSCILLATOR

Richard H. Winkler, Palo Alto, Calif., assignor, by mesne assignments, to Monogram Precision Industries, Inc., Culver City, Calif., a corporation of California

Application October 4, 1957, Serial No. 688,317

11 Claims. (Cl. 315—35)

This invention relates to electron tube oscillators for generating electromagnetic microwaves.

Briefly stated, according to certain aspects of this invention, a backward-wave oscillator tube comprises a microwave resonator containing a serpentine wave-transmitting passage having non-dissipative wave reflecting terminations at each of its ends, so that electromagnetic microwaves within the resonator travel back and forth repetitively through the serpentine passage. In contrast to conventional backward-wave oscillators, the wave-transmitting passage is electrically short—as short as one-quarter wavelength at the oscillation frequency, for example—and no attenuator is used. A beam of electrons is supplied along a path that repetitively crosses the serpentine wave-transmitting passage, and the electron velocity is made slightly greater than the phase velocity of a backward-wave space harmonic of the electromagnetic waves, so that energy is transferred from the beam to the microwaves in accordance with well-known principles.

Because resonators are employed, the new oscillator tubes are essentially fixed-frequency devices, operable approximately at a limited number of harmonically related frequencies only although they can be tuned by providing either electrical or mechanical means for adjusting the effective resonator length. The new tubes are exceptionally compact and simple in construction, and are capable of operating at relatively high electrical efficiencies compared to other tubes designed for equally high frequencies. The exceptionally short length of the new tubes is particularly advantageous, because the electron beam is sufficiently short that the heavy focusing magnets and the like required in conventional backward-wave oscillators are not needed.

The foregoing and other aspects of this invention may be better understood from the following illustrative description and the accompanying drawings. The scope of the invention is defined by the appended claims.

In the drawings:

Fig. 1 represents a lengthwise section of a new backward-wave oscillator tube;

Fig. 2 is a transverse section taken along the line 2—2 of Fig. 1;

Fig. 3 represents a lengthwise section of another new backward-wave oscillator tube;

Fig. 4 is a transverse section taken along the line 4—4 of Fig. 3;

Fig. 5 represents a lengthwise section of still another new backward-wave oscillator tube; and

Fig. 6 is a lengthwise section taken along the line 6—6 of Fig. 5, in a plane perpendicular to the plane of Fig. 5.

In Figs. 2, 4 and 6, the lines 1—1, 3—3 and 5—5 represent the planes of Figs. 1, 3 and 5, respectively.

An example of a backward-wave oscillator tube incorporating certain principles of this invention is illustrated in Figs. 1 and 2 of the drawings. A hollow, right circular cylindrical, metal envelope 1 is divided into two length-

2

wise sections by a transverse metal partition 2 having a circular aperture 3 through its center. The left end of the cylindrical envelope is closed by an insulating base member 4, while the right end opens into an end of a conventional rectangular waveguide 5. A conventional microwave window 6 is provided across the rectangular waveguide so that the enclosed space to the left of the window 6 (as viewed in Fig. 1), including all of the space within envelope 1, can be and is evacuated to the extent customary in high-vacuum electron tubes.

Within evacuated envelope 1 and to the left of partition 2 (as viewed in Fig. 1), there is a conventional electron gun comprising a heater filament 7, a cathode 8, and a focusing electrode 9. Partition 3 forms the first anode or accelerating electrode of the electron gun. The usual supply leads to the heater, cathode and focusing electrode pass through insulating base 4, as shown. The electron gun supplies a focused beam of electrons, represented in the drawing by broken line 10, that pass through aperture 3 and move from left to right along the longitudinal axis of cylindrical envelope 1. Within the envelope 1 and to the right of partition 2, there is a microwave resonator composed essentially of the conductive cylindrical envelope and two conductive metal plates 11 and 12 disposed side-by-side in a common diametric plane of the cylindrical envelope. A transverse section of the resonator is shown in Fig. 2.

Each of the two plates 11 and 12 has a toothed edge in non-contacting, interdigitated relation with the toothed edge of the other plate. In the embodiment illustrated in Figs. 1 and 2, plate 12 has two teeth 13 and 14 interdigitated with two teeth 15 and 16 of plate 11. Thus, there is defined, between the toothed edges of plates 11 and 12, an open-sided, serpentine, wave-transmitting passage 17. Each of the three teeth 13, 15 and 17 has a circular aperture 3' in alignment with aperture 3 of partition 2, so that electron beam 10 can pass through each of these three teeth. In the embodiment illustrated, tooth 14 has no such aperture and acts as a collector electrode for the electron beam. It is evident that the electrons of beam 10 move along a path that repetitively crosses the serpentine, wave-transmitting passage 17.

At the end of passage 17 that is nearest the electron gun, and therefore first crossed by the moving electrons, plates 11 and 12 are directly connected together by conductive partition 2. Therefore, partition 2 closes and provides a microwave, short-circuit termination across the left end of serpentine passage 17. The right end of passage 17 is terminated in a microwave open circuit.

Thus, both ends of wave-transmitting passage 17 are provided with nondissipative wave-reflecting terminations, whereby microwaves within the resonator are multiply reflected from the two terminations and travel back and forth repetitively through the serpentine passage 17. Since one end of the wave-transmitting passage is effectively short-circuited while the other end is effectively open-circuited, it is evident that the resonant frequencies of the resonator correspond to wavelengths at which the length of passage 17 is approximately equal to an odd integral number of quarter wavelengths. However, all such frequencies are not necessarily resonant frequencies of the resonator, for reasons that will appear as the description proceeds.

Throughout its length, plate 12 is electrically connected to cylindrical envelope 1. On the other hand, plate 11 is separated from plate 1 except at one end, where it is connected to plate 1 through transverse partition 2. Therefore, with respect to microwave frequencies, plate 11 is insulated from envelope 1 throughout a major portion of its length. A certain amount of similarity to a coaxial transmission line is apparent. In fact, the structure illustrated will support electromagnetic waves in

microwave modes of a type commonly associated with coaxial transmission lines. A noteworthy characteristic of such modes, of importance to the structure illustrated, is that such coaxial wave-transmission structures have no low-frequency cutoff. For example, if a D.C. electric source were connected between plate 11 and envelope 1 at the open-circuited end of the resonator, direct current would be transmitted to the shorted end of the structure without any losses except those due to conductor resistance.

On the other hand, there are significant differences between the structure shown in Figs. 1 and 2 and a short section of an ordinary coaxial transmission line. In particular, the interdigitated structure that defines serpentine passage 17 supplies a heavy capacitive loading to the line and concentrates the microwave electric field within and near the serpentine passage. Such a structure does have a high-frequency cutoff corresponding to a wavelength at which the length of each tooth (in a direction transverse to the longitudinal axis of cylindrical envelope 1) is approximately equal to one-half wavelength.

The resonant frequencies of the resonator are those frequencies that lie between the low-frequency cutoff (zero frequency in this case) and the high-frequency cutoff, and that also correspond to wavelengths at which the serpentine length of passage 17 is approximately equal to an odd integral number of quarter wavelengths. In the structure illustrated in Figs. 1 and 2 it is evident that there are four such resonant frequencies. The lowest resonant frequency is the one corresponding to a wavelength approximately four times as long as the serpentine length of passage 17. The other resonant frequencies are the third, fifth and seventh harmonics of the lowest resonant frequency. The oscillator illustrated in Figs. 1 and 2 is essentially a fixed-frequency device, operable approximately at one of these four resonant frequencies only.

From the foregoing considerations, it is evident that the structure illustrated in Figs. 1 and 2 has certain characteristics of a low-pass filter. It is well known that numerous space harmonics are associated with electromagnetic waves transmitted along filter-like circuits. The present structure is no exception. In general, these space harmonics have phase velocities that are very small compared to the velocity of light, and therefore are capable of being approximately matched by easily produced electron velocities for producing energy-transferring interactions between the electromagnetic waves and a moving stream of electrons. In the resonator structure under consideration, the microwaves travel back and forth repetitively through serpentine passage 17, and therefore there are both forward-wave and backward-wave space harmonics having phase velocities traveling in the same direction as the electron beam.

In principle, the electron velocity could be approximately matched to the phase velocity of any one (or sometimes more) of the space harmonics to obtain an energy-exchanging relationship between the electron beam and the electromagnetic wave. In practice, with the short structures used in practicing this invention, interactions usually occur only with the first (fastest phase velocity) backward-wave component. The reason is that this space harmonic has the highest coupling impedance to the electron beam, and therefore requires the lowest beam current to establish and to sustain microwave oscillations. The higher-order space harmonics in particular have much lower coupling impedances to the beam, and consequently are much less likely to interact sufficiently for the production of sustained microwave oscillations.

In some cases, particularly when operating at the lowest resonant frequency of the resonator, appreciable interactions may occur with both backward-wave and forward-wave space harmonics of the lowest order. However, no disadvantageous results follow from this, because the resonator length restricts the build-up of oscillations to certain fixed, harmonically related frequencies, as here-

inbefore explained, and the frequencies of first-order forward-wave and backward-wave interaction are sufficiently close that oscillations will usually occur at only one of these fixed frequencies for a given beam voltage.

Like other filter-type circuits, the resonator disclosed in Figs. 1 and 2 is dispersive. That is, the phase velocity of each space harmonic varies considerably as a function of frequency. Since energy-exchanging interactions occur only when the electron velocity is approximately equal to the phase velocity of a space harmonic, the beam voltage determines which of the several resonant frequencies of the resonator will be taken by the oscillations that are set up. This can be controlled in the usual manner by varying the potential of the cathode relative to the potential of envelope 1 and parts connected thereto.

For example, a relatively small beam voltage produces a correspondingly small electron velocity, which may set up in the resonator oscillations at the lowest resonant frequency corresponding to a wavelength approximately four times as long as the serpentine length of passage 17. A somewhat higher beam voltage may set up oscillations at the third harmonic frequency, at which serpentine passage 17 is approximately three-quarters of a wavelength long. A still higher beam voltage may excite oscillations at the fifth harmonic frequency, etc. The tube is generally operated at frequencies such that the length of passage 17 is less than one wavelength.

Another distinction between the present tube and a conventional backward-wave oscillator may be noted at this point. In backward-wave oscillators, electromagnetic wave energy is transmitted in a direction counter to the electron flow. In conventional tubes, wave reflections are minimized with attenuators, and the major energy flow is in this one direction. Furthermore, a fairly long (many wavelengths) slow-wave structure is used, which usually has a substantially constant impedance along its length. Consequently, the microwave electric field associated with the generated microwaves is strongest at that end of the slow-wave structure nearest the electron gun, and is relatively weak at the collector end of the slow-wave structure.

In the tube illustrated in the Figs. 1 and 2, conditions are quite different. As in a conventional traveling-wave tube, electromagnetic waves traveling from right to left through passage 17 (as viewed in Fig. 1) gain energy by backward-wave interaction with the electron beam. However, the electromagnetic waves are reflected at both ends of passage 17, and travel repetitively back and forth through the serpentine wave-transmitting passage. Consequently, the magnitude of the electromagnetic wave energy is substantially constant throughout the length of the slow-wave structure. However, the microwave electric field, which interacts with the electron beam, is not constant.

Assume, for example, that the oscillation frequency corresponds to the lowest resonant frequency of the resonator, at which passage 17 is approximately one-quarter wavelength long. As is well known, a quarter-wave resonant structure exhibits a standing-wave pattern having a voltage minimum at the short-circuited end and a voltage maximum at the open-circuited end of the resonator. Consequently, in the structure illustrated, the microwave electric field, which interacts with the electron beam, is weaker where the electrons first enter the field, and stronger at the collector end of the structure. This is just the reverse of the situation in conventional backward-wave oscillators. An important end result is a higher electrical efficiency in the new tubes.

This can be understood from the following considerations. Near the point where the electron beam first enters the microwave field, the chief effect of the interaction between the electric field and the beam is a velocity modulation of the beam, which absorbs energy from the microwave field. The stronger the microwave elec-

tric field is at this point, the greater will be the energy extracted from the electromagnetic waves. Further downstream in the electron beam, the electrons become more or less bunched due to their previous velocity modulation, and can then transfer energy back to the electromagnetic wave. In this process, there is a net reduction in the electron velocity, which supplies the energy whereby an overall gain in the microwave system can be accomplished to produce sustained oscillations and to permit the withdrawal of useful microwave energy. The greater the net decrease in electron velocity, the greater the amount of energy transferred to the electromagnetic wave, and the higher the electrical efficiency of the oscillator. Ideally, all of the electron velocity would be converted into electromagnetic energy, and one hundred percent efficiency would be realized. In practice this is not attainable, but for highest efficiency it should be approached as closely as possible.

In order to slow down the electrons as much as possible, the microwave electric field at the collector end of the slow-wave structure should be relatively strong, and to prevent an excessive transfer of the energy back to the electron beam the microwave electric field at the other end of the slow-wave structure should be relatively weak. It is evident that the new tube provides the strongest electric field where it is most useful, while conventional backward-wave oscillator tubes do not. This advantageous characteristic of the new tube is particularly evident at the lowest operating frequency, at which the resonator is effectively one-quarter wavelength long, and progressively becomes less evident at the higher operating frequencies. But even at the highest operating frequency of the new tubes, the advantage over conventional traveling-waves tubes is considerable.

Another example of a backward-wave oscillator tube incorporating certain principles of this invention is illustrated in Figs. 3 and 4. An electrically conductive, hollow, evacuated, right circular cylindrical metal envelope 18 is closed at its upper end (as viewed in Fig. 3) by a conductive metal plate 19 and is closed at its lower end by an insulating base member 20. The envelope is divided into two lengthwise sections by an electrically conductive, metal, transverse partition 21 having a small circular aperture 22 through its center. Within envelope 18 below partition 21, there is a conventional electron gun having a heater filament 23, a cathode 24 and a focusing electrode 25, for supplying a focused beam of electrons moving through aperture 22 along the longitudinal axis of cylindrical envelope 18, as represented in the drawing by broken line 26. The usual electrical supply leads for the electron gun pass through insulating base member 20 in the usual manner, as shown.

Within envelope 18 above partition 21 (as viewed in Fig. 3), there are two conductive metal plates 27 and 28 disposed side-by-side in a common diametric plane of the cylindrical envelope and forming in combination with the envelope a microwave resonator. A transverse section of this resonator is shown in Fig. 4. Each of the plates 27 and 28 has a toothed edge interdigitated with but separated from the toothed edge of the other plate. Thus, the toothed edges of plates 27 and 28 cooperate to form an open-sided, serpentine, wave-transmitting passage 29. Each of the interdigital teeth has an aperture 22' aligned with aperture 22 to permit the passage of electron beam 26 through the teeth. It is apparent that the electrons repetitively cross the serpentine, wave-transmitting passage 29.

The end tooth 30 of plate 27 is extended somewhat in length relative to the other teeth, as shown. A coaxial transmission line has an outer conductor 31 attached to and electrically connected to end plate 19, and has an inner conductor 32 that extends through an

iris 33 in plate 19 and is connected to tooth 30. An insulator 34 within the coaxial line serves as a vacuum seal.

Plates 27 and 28 are both connected to conductive partition 21. Therefore, partition 21 closes and provides a microwave short-circuit termination across the lower end of the serpentine, wave-transmitting passage 29. Plates 27 and 28 are both connected to conductive end plate 19 also. Consequently, end plate 19 closes and provides a microwave short-circuit termination across the upper end of serpentine passage 29. Thus, at microwave frequencies, serpentine passage 29 is short-circuited at both of its ends. Therefore, microwaves are reflected at both ends of the passage 29, and travel back and forth repetitively through passage 29. Since both terminations are microwave short circuits, the resonant frequencies of this resonator correspond to wavelengths at which the serpentine length of passage 29 is approximately equal to an integral number of half wavelengths.

Plates 27 and 28 are both electrically connected throughout their length to conductive cylindrical envelope 18. Certain similarities between this resonator structure and a double-ridged circular waveguide are apparent. The resonator structure illustrated in Figs. 3 and 4 supports electromagnetic waves in microwave modes of a type commonly associated with ridged waveguides, and, like a ridged waveguide, it has a low-frequency cutoff that is approximately proportional to its diameter.

Unlike an ordinary ridged waveguide, the resonator structure illustrated in Figs. 3 and 4 is capacitively loaded by the interdigitated teeth of plates 27 and 28, and has characteristics somewhat analogous to a bandpass filter circuit. It has a high-frequency cutoff corresponding to a wavelength at which each of the interdigitated teeth is approximately one-half wavelength long. The resonant frequencies of the resonator lie between the low and high cutoff frequencies, and in addition must be harmonics of that frequency corresponding to a wavelength of approximately twice the serpentine length of passage 29. To avoid losing the lowest resonant frequency, the diameter of cylindrical envelope 18 preferably is made sufficiently large that the low-frequency cutoff falls below the frequency at which passage 29 is one-half wavelength long.

The operating principles of this tube are very similar to those of the tube illustrated in Figs. 1 and 2. Interactions between the electron beam and the electromagnetic wave take place in the lower half of the resonator (as viewed in Fig. 3) in substantially the same manner as in the Fig. 1 apparatus. The upper half of the resonator serves principally as an impedance-transforming termination for the lower half of the resonator. Toward the top of serpentine passage 29, the microwave electric field is weak because of the short-circuit termination at the top end of the serpentine passage. This is desirable, because in this region whatever remains of the electron beam is likely to be poorly modulated, to the extent that the beam may begin absorbing energy from rather than supplying energy to the electromagnetic wave. The weakness of the electric field minimizes this undesirable energy transfer.

Furthermore, in practice the electron beam usually is well-focused only to about the center of the resonator, since no magnetic field or other focusing means is employed beyond the electron gun. As the beam becomes de-focused and spreads, a portion of the beam is intercepted by each of the interdigital teeth, and in consequence the beam current decreases substantially toward the collector end of the resonator.

The embodiment illustrated in Fig. 3 does have a somewhat longer high-impedance interaction region than does the embodiment illustrated in Fig. 1, and also the embodiment illustrated in Fig. 3 is capable of operation at both odd and even harmonics of the lowest resonant frequency, whereas the Fig. 1 embodiment can operate at odd harmonic frequencies only. For a given frequency of opera-

tion, the embodiment illustrated in Fig. 3 is somewhat larger than the embodiment illustrated in Fig. 1. These differences may be advantages or disadvantages of one embodiment relative to the other, depending upon the particular environment and circumstances in which the tubes are to be used.

Still another example of a backward-wave oscillator tube incorporating certain principles of this invention is illustrated in Figs. 5 and 6. An evacuated, hollow, right circular cylindrical, electrically conductive, metal envelope 35 is closed at one end by a metal end plate 36 and is closed at the other end by an insulating base member 37. The space within the envelope is divided into two lengthwise sections by an electrically conductive, metal, transverse partition 38 having a small circular aperture 39 through the center, as shown.

To the left of partition 38 (as viewed in Figs. 5 and 6) there is a conventional electron gun comprising a heater filament 40, a cathode 41 and a focusing electrode 42. Electrical supply leads for the electron gun extend through insulating base member 37 in the usual manner, as shown. The electron gun provides a focused beam of electrons, represented in the drawing by broken line 43, that pass through aperture 39 and move from left to right along the longitudinal axis of cylindrical envelope 35. Partition 38 acts as a first anode or accelerating electrode of the electron gun. The electrons are collected by end plate 36, which acts as a collector electrode for the electron beam.

Within envelope 35 to the right of partition 38 (as viewed in Figs. 5 and 6) there are two electrically conductive, metal plates 44 and 45 disposed side-by-side in a common diametrical plane of cylindrical envelope 35. Each of the plates 44 and 45 has a toothed edge interdigitated with but separated from the toothed edge of the other plate, as shown. For example, plate 44 may be provided with three projecting teeth 46, 47 and 48 that are interdigitated with three teeth 49, 50 and 51 projecting from plate 45. The toothed edges of plates 44 and 45 cooperate to define a serpentine, wave-transmitting passage 52.

The right end of plate 44 is connected to the conductive cylindrical envelope 35, while the left end of plate 45 is connected to envelope 35. Furthermore, tooth 46 of plate 44 is connected to envelope 35 through a conductive bar 53, and tooth 51 of plate 45 is connected to envelope 35 through a conductive bar 54, for purposes hereinafter explained. Otherwise, plates 44 and 45 are separated from envelope 35 so that, at microwave frequencies, major portions of the lengths of plates 44 and 45 are insulated from envelope 35. Thus, the structure is somewhat analogous to a shielded-pair transmission line, and is capable of supporting electromagnetic waves in microwave modes of a type commonly associated with shielded-pair transmission lines.

The structure illustrated in Figs. 5 and 6 differs from a short section of an ordinary shielded-pair line in that the interdigitated teeth of plates 44 and 45 provide capacitive loading and form a filter-type slow-wave structure capable of supporting electromagnetic waves with space harmonics that have small phase velocities compared to the velocity of light. Furthermore, the structure is electrically short, and is terminated at each end by nondissipative wave-reflecting terminations to form a microwave resonator.

The two conductive bars 53 and 54 are bent into a somewhat S-shaped configuration, as shown, and have outer ends that are connected to conductive cylindrical envelope 35. Bars 53 and 54 act as short stub transmission lines and provide nondissipative reactive terminations at each end of the serpentine, wave-transmitting passage defined by the interdigitated structure. Assume, for example, that the serpentine passage 52 is approximately one-quarter wavelength long at a particular operating frequency, and that each of the bars 53 and 54 forms a stub transmission line approximately one-eighth wave-

length long. It is evident that the structure as a whole is approximately one-half wavelength long, and forms a resonator wherein electromagnetic waves are multiply reflected and travel repetitively back and forth through 5 serpentine passage 52. Because passage 52 is a quarter-wave section located approximately at the electrical center of a half wave resonator, the microwave electric field has an appreciable amplitude throughout the length of serpentine passage 52. Consequently, there is a fairly high coupling impedance between the electromagnetic waves and the electron beam throughout the length of passage 52.

The two bars 53 and 54 need not be precisely the same length. By making bar 53 somewhat shorter than bar 15 54, as shown in Fig. 6, the microwave electric field can be made somewhat weaker at the end of passage 52 nearest the electron gun than it is at the other end of the passage, which is desirable in accordance with principles herein-before disclosed. Thus, bar 53 is a means for providing 20 a microwave electric field that is relatively small, but not zero, at the left end of passage 52, while bar 54 provides a terminating means at the right end of passage 52 such that the structure as a whole is a half-wave resonator. It is evident that the structure will also resonate at higher 25 frequencies corresponding to wavelengths at which the structure as a whole has an electrical length approximately equal to an integral multiple of a half wavelength. Therefore, the structure has a plurality of harmonically related resonant frequencies, lying between a lower cutoff 30 frequency and a higher cutoff frequency, similar to the other resonators herein described.

The electromagnetic waves supported in the resonator travel through serpentine passage 52 and there produce space harmonics having phase velocities that are small 35 compared to the velocity of light, in the usual manner of interdigital wave-transmission structures. When the electron velocity of beam 43 is made approximately equal to the phase velocity of one of these space harmonics, energy-transferring interactions occur between the electromagnetic waves and the electron beam so that, when the electron velocity is slightly greater than the phase 40 velocity, energy is transferred from the electron beam to the electromagnetic waves and sustained oscillations are produced approximately at a resonant frequency of the 45 resonator.

Coupling means for withdrawing electromagnetic microwave energy from the resonator may, for example, comprise a coaxial transmission line having an outer conductor 55 connected to conductive end plate 36 of the 50 evacuated envelope and an inner conductor 56 that extends through an iris 57 in the end plate and is bent into an inductive coupling loop 58. Microwave current passing through bar 54 and other parts of the resonator structure produces a microwave magnetic field that links the 55 coupling loop 58 and supplies microwave energy to the output transmission line by ordinary transformer action. An insulator 59 within the transmission line serves as a vacuum seal for maintaining the vacuum within envelope 35.

It should be understood that this invention in its broader aspects is not limited to specific examples herein illustrated and described, and that the following claims are intended to cover all changes and modifications within the true spirit and scope of the invention.

What is claimed is:

1. A backward-wave oscillator comprising the following combination: an evacuated microwave resonator containing a serpentine wave-transmitting passage, said passage having non-dissipative wave-reflecting terminations 70 at both of its ends so that electromagnetic waves within said resonator are repetitively reflected at said terminations and travel back and forth through said passage, whereby there are produced backward-wave space harmonics having phase velocities that are small compared to the velocity of light; means for providing a beam of elec-

trons moving along a path repetitively crossing said serpentine passage at a velocity approximately equal to the phase velocity of one of said backward-wave space harmonics, so that said beam supplies energy to said electromagnetic waves, whereby sustained electromagnetic oscillations are generated at a resonant frequency of said resonator; and coupling means for withdrawing microwave electromagnetic energy from said resonator.

2. A backward-wave oscillator as defined in claim 1, wherein the serpentine length of said passage is smaller than one wavelength of said electromagnetic waves at the lowest resonant frequency of said resonator.

3. A backward-wave oscillator as defined in claim 1, wherein said wave-reflecting terminations are a microwave short circuit and a microwave open circuit, respectively, said short circuit being at that end of said serpentine passage that is first crossed by said electrons, and said resonator has a resonant frequency at which the length of said serpentine passage is approximately equal to a quarter wavelength of said electromagnetic waves.

4. A backward-wave oscillator as defined in claim 1, wherein both of said wave-reflecting terminations are microwave short circuits, and said resonator has a resonant frequency at which the length of said serpentine passage is approximately equal to a half wavelength of said electromagnetic waves.

5. A backward-wave oscillator as defined in claim 1, wherein said wave-reflecting terminations are microwave reactances provided by stub transmission lines.

6. A microwave electron tube comprising the following combination: an evacuated envelope; two coplanar, electrically conductive plates within said envelope, each of said plates having a toothed edge interdigitated with but spaced from the toothed edge of the other plate, defining an open-sided serpentine passage between the two plates for the transmission of electromagnetic waves, said passage having non-dissipative wave-reflecting terminations at both of its ends, so that said waves travel back and forth repetitively through said passage, thus forming a microwave resonator having a plurality of resonant frequencies; and electron gun means within said envelope for providing an electron beam that repetitively crosses said serpentine passage in energy-exchanging interacting relation with said electromagnetic waves.

7. A microwave electron tube comprising the following combination: an electrically conductive, evacuated, hollow cylinder; two electrically conductive plates disposed side-by-side in a common diametric plane within said cylinder, said plates having interdigitated, toothed, adjacent edges defining an open-sided serpentine passage for the transmission of electromagnetic waves with space harmonics having phase velocities that are small compared to the velocity of light, said passage having non-dissipative wave-reflecting terminations at both of its ends so that said waves travel back and forth repetitively through said passage, thus forming a microwave resonator having a plurality of resonant frequencies; means for providing a beam of electrons moving along a path repetitively crossing said serpentine passage at a velocity approxi-

mately equal to the phase velocity of one of said space harmonics so that said beam supplies energy to said electromagnetic waves; and coupling means for withdrawing microwave energy from said resonator.

5 8. A microwave electron tube as defined in claim 7, wherein with respect to microwaves, one of said plates is electrically connected throughout a major portion of its length to said cylinder while the other of said plates is electrically insulated throughout a major portion of its length from said cylinder, so that said resonator supports electromagnetic waves in microwave modes of a type commonly associated with coaxial transmission lines.

9. A microwave electron tube as defined in claim 7, wherein, with respect to microwaves, both of said plates are electrically connected throughout major portions of their lengths to said cylinder, so that said resonator supports electromagnetic waves in microwave modes of a type commonly associated with ridged waveguides.

10 10. A microwave electron tube as defined in claim 7, wherein, with respect to microwaves, both of said plates are electrically insulated throughout major portions of their lengths from said cylinder, so that said resonator supports electromagnetic waves in microwave modes of a type commonly associated with shielded-pair transmission lines.

15 11. An oscillator for supplying electromagnetic waves to a waveguide, comprising an electrically conductive, hollow cylindrical envelope having an open end attached to and opening into the waveguide, two electrically conductive plates disposed side-by-side in a common diametric plane within said cylindrical envelope, one of said plates being electrically and mechanically connected substantially throughout its length to said envelope, the other of said plates being electrically and mechanically separated substantially throughout its length from said envelope, said plates having interdigitated, toothed, adjacent edges defining an open-sided serpentine passage for the transmission of electromagnetic waves, the edges of said plates nearest to the waveguide being electrically separated to form an electrical open circuit at that end of the serpentine passage, a conductive, transverse partition extending across said envelope, the edges of said plates farthest from the waveguide being electrically and mechanically connected to said partition to form an electrical short circuit at that end of the serpentine passage, said partition and a plurality of said teeth containing apertures aligned substantially along the longitudinal axis of said cylindrical envelope, and electron gun means disposed within said envelope on the other side of said partition from the waveguide for providing an electron beam through such apertures.
